Specification for Design.

Patented Mar. 9, 1920.

Application filed June 26, 1919. Serial No. 307,038. Term of patent 14 years.

To all whom it may concern:

Be it known that I, GEORGE E. HAZARD, a citizen of the United States, residing at Rochester, in the county of Monroe and State of New York, have invented a new, original, and ornamental Design for Air-Pump Crank-Shafts and Gear Housings, of which the following is a specification, reference being had therein to the accompanying drawings.

In the accompanying drawing—

Figure 1 is a perspective view of my new design for an air pump crank shaft and gear housing.

Fig. 2 is a top plan view of the same.

I claim:—

The ornamental design for an air pump crank shaft and gear housing as shown.

In testimony whereof I hereunto affix my signature.

GEORGE EDGAR HAZARD.
